AUTOMOBILE OIL COOLER

Filed April 5, 1927

UNITED STATES PATENT OFFICE.

CHARLES J. MACINTOSH, OF OAKLAND, CALIFORNIA.

AUTOMOBILE OIL COOLER.

Application filed April 5, 1927. Serial No. 181,113.

The invention relates to a simple, inexpensive and practical device that can be attached to any type of automobile, and which, by the use thereof, will increase the life and the efficiency of the motor by continuously cooling the oil that is pumped to the bearings.

It is one of the objects of the invention to, first, provide a device of the character described and to mount same in front of the fan and radiator of an automobile so as to obtain the highest efficiency possible from the cooler; and second, it is another object of the invention to improve the construction of oil coolers by providing means that will eliminate any and all chances for gas to form and remain in the cooler that will obstruct or in any way interfere with the cooling area of the device.

A further object of the invention is the provision made to keep the outer periphery of the cooler tight against the radiator and thereby provide a positive enclosed opening through the cooler and radiator to the fan.

The invention possesses other objects and features of advantage, some of which, with the foregoing, will be made manifest in the following description of the preferred form of the invention which is illustrated in the drawings accompanying and forming part of the specification.

It is to be understood that it is not intended to limit the invention to the embodiment shown by said drawings and description, as variations may be adopted within the scope of the invention as set forth in the claims.

In the accompanying drawings:

Figure 1 is a plan of the cooler, with the top plate removed, showing the baffle plate that forms a passage-way for the oil to travel around the tubes.

Figure 2 is a side elevation of the cooler showing a portion thereof in section.

Figure 3 is a front view of an automobile showing an oil cooler fastened to the frame thereof and mounted in front of the radiator.

Figure 4 is a view showing the relation of the cooler to the pump, the fan and the radiator.

According to the construction shown, the numeral 5 designates a housing, preferably forming a cylindrical chamber and into which there is provided an outer end plate 6 and an inner end plate 7 forming a liquid tight container as shown in Figure 2. A plurality of tubes 8 are mounted into the housing, and extend through and are substantially fastened

in each of the end plates 6 and 7 and are arranged in series as illustrated, with space therebetween so that oil may easily travel around the tubes and out of the housing. The baffle 9 is preferably made of a single piece of material and is shaped into the form of an involute so as to provide a long continuous cooling area for the oil to travel in passing through the cooler. The oil inlet 10 is preferably centrally located in the end plate 6 and the outlet 11 is preferably located in the cylindrical wall of the housing 5.

A serious problem existing in the present type of oil coolers is the forming of gas by the hot oil, a portion of which, regardless of the shape of the baffle, remains in the cooler and forms gas pockets therein that covers and obstructs a certain amount of the cooling area of the device. A preferred method of eliminating said gas pockets consists in the providing of a plurality of holes 12 in the baffle and locating the holes in pocket forming portions thereof so that the gas will leak out of said holes 12 and will readily pass out of the cooler.

The housing 5 is provided, on the outer cylindrical surface thereof, with lugs 14 which are fastened to a pair of substantial braces 15 that are detachably mounted on the frame 16 of an automobile and adapted to be rigidly secured thereon. As hereinbefore stated, it is desired to mount the cooler in front of the fan of the automobile and against the radiator. Provision is made to permit the cooler to fit tight against the radiator by providing, around the end of the housing that extends toward the radiator, a ring 17, preferably composed of a refractory material, so that portions of the ring 17 may be forced tight against and into the radiator 18, thereby forming a continuous unbroken opening through the cooler and the radiator, and to the fan.

In Figures 3 and 4, there is illustrated a cooler 17 detachably mounted on an automobile. The numeral 19, Figure 4, is shown as comprising the pump of an automobile, having a pipe 20 leading to the suction thereof from the oil sump, and another pipe 21 leading from the discharge of the pump to the inlet 10 of the cooler. The device is preferably mounted on the automobile so that the outlet 11 is in the uppermost position, and a pipe 22, Figure 4, leads from said outlet to the bearing oil inlet 24. A drain 26 having a plug 27 is provided in the lowermost surface of the housing 5 to allow for draining oil out of the cooler.

From the foregoing it will be observed that by mounting the device in front of the fan 25 and the radiator 18, cool air is drawn through the tubes 8 by the fan 25 and oil from the 5 sump is pumped to the cooler inlet 10 and into the cooler and travels around the tubes 8 and through the involute passage-way formed by the baffle 9 and through the outlet 11 and the pipe 22 and into the motor bearing oil-inlet 10 24 providing the working parts of the motor 28 with cooled oil.

The device is simple, has no working parts, can be mounted on any type of automobile, provides film lubrication, increases the efficiency of the motor by reducing frictional 15 losses, prevents burnt out bearings and increases the radiation or the cooling area of the motor by providing cooler oil for the working parts.

Having thus illustrated and described a certain form of construction and arrangement of parts pertaining to the invention, it is to be understood that the improvements 20 may be embodied on any type of oil cooling device, which, obviously, may be built in any suitable manner, the present illustration not being utilized as indicating the only form of construction into which the parts may be made; and it is desired to include in this application for Letters Patent of the United 25 States of America all that comes within the range of the invention as set forth in the claims hereinafter mentioned.

What is claimed:

- 35 1. A device of the character described, mounted on an automobile, comprising a housing; end plates mounted therein; said housing and end plates forming a cylindrical chamber; a plurality of tubes mounted within 40 the chamber and extending into and through said end plates; an oil inlet leading from the oil pump of the automobile to and in said chamber; an oil outlet located in the upper portion of the chamber and leading to the 45 motor; and a continuous baffle, forming an involute passage-way in the chamber from the inlet to the outlet for allowing the oil to be circulated around the tubes in and through said chamber.
- 50 2. A device of the character described, comprising a housing; end plates mounted therein; said housing and end plates forming a liquid-tight chamber; a plurality of tubes mounted within the chamber and extending

into and through said end plates; an oil inlet 55 and outlet in the chamber; means for circulating oil therethrough; a baffle, forming an involute passage-way in the chamber from the inlet to the outlet; and a plurality of openings in the baffle to allow the gas that forms in said involute passage-way to travel out of the chamber.

3. A device of the character described, mounted in front of the radiator of an automobile; the said device comprising a housing, 60 forming a liquid tight chamber; a plurality of tubes mounted within the chamber and extending therethrough; an oil inlet leading from the oil pump of the automobile to the chamber; an oil outlet leading from the chamber to the motor; a baffle, forming an involute passage-way in the chamber from the inlet to the outlet; and means for sealing the housing 65 to the radiator.

4. A device of the character described, detachably mounted in front of the radiator of an automobile; the said device comprising a housing, 70 forming a circumferential liquid tight chamber; a plurality of tubes longitudinally mounted within the chamber and extending through the end walls thereof; an oil inlet, leading from the oil pump of the automobile to one end of the chamber; an oil outlet leading from the circumferential side of the chamber to the motor parts; a baffle, 75 extending from end to end within the chamber and forming an involute passage-way therein, for the oil to travel around the tubes, from the inlet to the outlet of said chamber; and means for detachably sealing the housing 80 to the radiator.

5. An oil cooler for an automobile; the said cooler comprising a housing; means for conveying air therethrough; means for circulating the motor lubricating oil around 85 said air conveying means and through said housing; the said cooler being mounted on to the automobile in front of the radiator thereof, to permit air to pass through the cooler before said air passes through the radiator, for the purpose of preventing the air from being heated by the radiator before it 90 passes through the cooler.

In testimony that I claim the foregoing I have hereto set my hand this twenty-second 105 day of March, 1927.

CHARLES J. MACINTOSH.
